DISPLAY SHELF

Robert L. Swartz, Madison, Wis., assignor to Oscar Mayer & Co., Inc., Chicago, Ill., a corporation of Illinois

Filed July 1, 1968, Ser. No. 12,562

Term of patent 14 years

Int. Cl. D6—01

U.S. Cl. D80—10

FIGURE 2 is a bottom plan view of the display shelf; FIGURE 3 is a side elevation of the display shelf; and FIGURE 4 is a front elevational view thereof.

The fragmentary broken line representation of supporting structure in FIGURES 1 and 4 is for purposes of illustration only.

I claim:

The ornamental design for a display shelf, as shown and described.
